UNITED STATES PATENT OFFICE.

THOMAS R. ROSIER, OF DAYTON, WASHINGTON TERRITORY.

FANNING-MILL.

SPECIFICATION forming part of Letters Patent No. 243,160, dated June 21, 1881.

Application filed March 29, 1881. (Model.)

To all whom it may concern:

Be it known that I, THOMAS R. ROSIER, of Dayton, in the county of Columbia, Washington Territory, have invented certain new and useful Improvements in Fanning-Mills; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my improved fanning-mill with sacking attachment connected thereto. Fig. 2 is a vertical longitudinal section of my mill. Fig. 3 is a horizontal section taken through the shoe.

This invention has reference to improvements in fanning-mills with means connected thereto for sacking the cleaned grain; and it consists in the combination and arrangement of the parts, substantially as hereinafter more fully set forth and claimed.

Referring to the accompanying drawings, A indicates a casing, within one end of which is hung the fan B, with its shaft provided with a pulley, a, and a gear-wheel, a', for imparting motion to the fan. The use of the pulley will be seen hereinafter. In the upper part of the

30 casing A is the hopper b. C is the shoe, hung within the opposite end of the casing A, with its sides adapted to play in openings in the sides of the casing, and supported by hangers c c, pivoted to the outside of the casing, to permit it to have a vibrating or shaking motion.

D is a lever pivoted in the inside of the case A, and extending transversely through and projecting a little beyond the outside of the 40 casing, to enable it to be conveniently connected by the pitman d to the eccentric or gear-driving wheel of the fan, by which motion may be imparted to the lever. This lever is connected by a spring-arm, d', to the shoe C, to transmit motion to the shoe, and by a rod, d², to the lower set of sieves, to impart motion to the latter, but in a contrary direction to that of the shoe having the upper set of sieves.

Within the shoe is arranged the coarse gang 50 of sieves E, to subject the grain to the first step in the cleaning process. An inclined board,

E', is arranged under the shoe, to conduct the falling grain to and allow it to pass upon lower finer set of screens or sieves below. From the discharging or lower end of the board E', and 55 from two cross-bars, e e, disposed at suitable intervals apart, and in the same inclination with the oppositely inclined lower sieve or sieves, dangle pieces of canvas, e' e² e³, about touching the lower sieve, the object of which 60 being to arrest the bounding motion of the elastic grains or seeds, and thus precipitate them with the other grain upon the sieve.

F is the lower sieve or set of sieves, with the sides of its frame adapted to move in grooves 65 in the inside of the casing A in an oppositely inclined plane to that of the shoe having the upper sieves. The grain is subjected to a second cleaning by being passed over this sieve or set of sieves to effect the thorough separation 70 of the grain and cockle.

Arranged under the sieve F, and supported upon cross-pieces of the supporting-uprights of the casing A, is a rack, G, composed of a series of edgewise boards, g, secured upon longitudinal parallel bars g', and with their upper edges placed in contact with the under side of the sieve F. This rack is to prevent the clogging of the sieve, and thus facilitate the cleaning process.

H is the sacking device, which consists of the base h, with its floor formed with a chute, h', and the elevator H', with the upper shaft of its endless bucket-belt provided with a pulley, h², with a belt, h³, passing around the pulley a upon the fan-shaft to impart motion to the elevator-belt. The elevator-stock H' has a discharging-spout, h⁴, with opposite pins or studs, h⁵, upon its inside, near its outer end, to permit of the slipping of the open end of the 90 sack thereon in readiness to receive the elevated grain. A cover, h⁶, with a downwardly-projecting lip, h⁷, hinged upon the upper end of the elevator-stock, is adapted to shut down upon the spout h⁴ and over the studs h⁵, and 95 thus secure the sack thereon. The sacking device is adjusted to the fanning-mill in the manner shown in Fig. 1, and hooked thereto, as seen in the same figure.

I is a lever connected by an adjusting-screw, 100 I', to the elevator-stock, and with a pulley in one end, over which passes the belt h³. The

lever I has a slot, *i*, through which the screw I' passes, to permit of the adjustment of the lever so as to tighten or loosen the belt upon its pulleys, by which the elevator can be put in 5 and out of operation, as may be desired.

Having thus fully described my invention, I claim and desire to secure by Letters Patent—

The combination of the frame A, the shoe C, the sieve-frame F, the elastic or spring bar *d'*, 10 secured to lever D, the connecting-rod *d'*, and

suitable operating mechanism, as herein described, for the purpose set forth.

In testimony that I claim the foregoing as my own I have hereto affixed my signature in presence of two witnesses.

THOMAS R. ROSIER.
